(57) **CLAIM**

The ornamental design for a set of base plates of folding tent storage bag, as shown and described.

DESCRIPTION

1. Set of base plates of folding tent storage bag

1.1: Perspective

1.2: Perspective

1.3: Front

1.4: Back

1.5: Left

1.6: Right

1.7: Top

1.8: Bottom

1.9: Perspective

1.10: Perspective

1.11: Front

1.12: Back

1.13: Left

1.14: Right

1.15: Top

1.16: Bottom

1.17: Perspective view showing the two parts

It's a set of base plates installed at the bottom of a folding tent storage bag; it contains two parts; reproductions 1-8 show the left part; reproductions 9-16 show the right part. The broken lines shown in the figures are for the purpose of illustrating portions of the set of base plates of folding tent storage bag and form no part of the claimed design. The additional broken lines shown in Figure. 1.17 that show the wheels and axle illustrate environmental information and form no part of the claimed design.
